(57) **CLAIM**

The ornamental design for an atomizer for electronic cigarette as shown and described.

DESCRIPTION

1. Atomizer for electronic cigarette
2. Atomizer for electronic cigarette

1.1: Front

1.2: Rear

1.3: Left

1.4: Right

1.5: Top

1.6: Bottom

1.7: Perspective

1.8: Perspective

2.1: Front

2.2: Rear

2.3: Left

2.4: Right

2.5: Top

2.6: Bottom

2.7: Perspective

2.8: Perspective

1.1 is a front view of a first embodiment of an atomizer for electronic cigarette showing our new design; **1.2** is a rear view thereof; **1.3** is a left view thereof; **1.4** is a right view

(Continued)

thereof; **1.5** is a top view thereof; **1.6** is a bottom view thereof; **1.7** is a front, bottom and right side perspective view thereof; **1.8** is a front, top and right side perspective view thereof; **2.1** is a front view of a second embodiment of the atomizer for electronic cigarette; **2.2** is a rear view thereof; **2.3** is a left view thereof; **2.4** is a right view thereof; **2.5** is a top view thereof; **2.6** is a bottom view thereof; **2.7** is a front, bottom and right side perspective view thereof; and **2.8** is a front, top and right side perspective view thereof.
